DESIGN FOR AN AUXILIARY TELEPHONE RECEIVER

Louis S. Scher, New York, N. Y.

Application May 9, 1942, Serial No. 106,840

Term of patent 7 years

To all whom it may concern:

Be it known that I, Louis S. Scher, a citizen of the United States, residing in New York city, in the county of Bronx and State of New York, have invented a new, original, and ornamental Design for an Auxiliary Telephone Receiver, of which the following is a specification, reference being had to the accompanying drawing, forming a part thereof.

Fig. 1 is a front elevational view of an auxiliary telephone receiver, showing my new design.

Fig. 2 is a side elevational view thereof.

Fig. 3 is a rear elevational view thereof.

The dominant features of the design reside in the portions shown in full lines.

I claim:

The ornamental design for an auxiliary telephone receiver, substantially as shown and described.

LOUIS S. SCHER.
